UNITED STATES PATENT OFFICE.

LEONARD CONOW, OF CORTE MADERA, CALIFORNIA, ASSIGNOR TO JOHN J. MAZZA, OF SAN FRANCISCO, CALIFORNIA.

OIL BURNER.

1,426,361.

Specification of Letters Patent. Patented Aug. 22, 1922.

Application filed November 26, 1920. Serial No. 426,372.

To all whom it may concern:

Be it known that I, LEONARD CONOW, a citizen of the United States, residing at Corte Madera, in the county of Marin and 5 State of California, have invented new and useful Improvements in Oil Burners, of which the following is a specification.

The present invention has special reference to an improved oil burner especially 10 designed for use in coal or wood cook stoves and particularly adapted for burning the lighter variety of oil, such as kerosene.

The primary object of the invention is to 15 provide an oil burner of the character described, which will be comparatively simple and inexpensive as to construction; which will be reliable and economical in use; and which may be easily and quickly installed in the fire box of an ordinary coal and wood 20 cook stove without necessitating any change in the construction of the stove, whereby said stove may be easily and cheaply converted into the oil burning type.

The invention possesses other advantages 25 and features, some of which, with the foregoing will be set forth at length in the following description wherein I shall outline in full that form of the invention which I have selected for illustration in the drawings 30 accompanying and forming a part of the present specification. In said drawings I have shown one form of the construction of my invention, but it is to be understood that I do not limit myself to such form since 35 the invention as expressed in the claim may be embodied in a plurality of forms.

Referring to the drawings:

Figure 1 is a fragmentary perspective view of the fire box of an ordinary cook 40 stove, showing the burner of my invention associated therewith, said burner being broken away for the sake of clearness of illustration.

Figure 2 is a longitudinal vertical sectional view through the burner of my invention.

Figure 3 is a transverse sectional view of the burner.

In carrying out one practical embodiment 50 of the invention as shown in the drawings there is provided a cast iron base 1 which is preferably of rectilinear outline and flat, so that it may be fitted into the fire box 2 of a cook stove as shown in Figure 1. The base 55 is adapted to rest upon the grating 3 in the

fire box and practically covers the entire floor of said fire box.

Extending through the bosses 4 formed on opposite sides of the base at the centre thereof is an internally screw threaded opening 5. The lower end of the opening is adapted to receive the fuel feed pipe not shown, whereas the upper end receives a short upwardly extending pipe 6. The pipe 6 supports and is turned into the lower side 65 of a preferably cylindrical generating or gasifying chamber 7, said chamber preferably being of cast iron and having its flat sides parallel with the upper face of the body. The chamber is relatively large but 70 of considerably less diameter than the width of the base so that said base extends outwardly from all sides of the chamber and close thereto.

Extending upwardly from the upper side 75 of the chamber 7 is a burner pipe 8 having a downwardly and outwardly curved upper portion 9. The free end of the pipe is closed as at 10 and at about the middle of the curved portion 9 in the under side thereof is 80 a burner orifice 11, through which fuel issues. This orifice is immediately over the upper flat side of the gasifying or generating chamber 7. Preferably, the curved portion 9 is turned so as to extend towards the 85 oven wall 12 of the fire box. Preferably formed integral with the base 1 on opposite sides of the chamber 7 are upwardly extending air intake tubes 13, the upper ends of which terminate near the upper side of the 90 chamber. These tubes open through the base and permit air, as a supporter of combustion, to flow from beneath the grating 3 up and around the chamber 7.

In the operation of the burner, fuel is directed into the chamber 7 and after said chamber becomes filled, the fuel passes upwardly through the burner pipe, escapes through the orifice 11, and drops into the upper side of the said chamber. When the 100 chamber and surrounding portions of the base are thoroughly covered with fuel, the feed of the fuel is cut off and the fuel is then ignited by having a paper torch or lighted match applied thereto. After the fuel has 105 burned on and around the chamber a few minutes and the chamber has become heated sufficiently to gasify the fuel therein, the fuel is turned on again and fed under pressure to the burner. Any suitable well known 110

means for feeding the fuel under pressure may be used. The fuel now fed under pressure is forcibly discharged in a gaseous or spray-like form onto the upper side of the 5 chamber and readily ignites as it strikes said chamber. The flame is deflected outwardly in a fan-like spread and covers a large area around the chamber so as to keep the chamber properly heated to gasify the 10 fuel in the chamber.

It will thus be seen that the burner of this invention will operate economically and provide an intense effective heat. If desired, the burner may be cast in one piece instead 15 of being formed of several parts as shown in the drawings. The large base covering the entire grating section 3 acts as a heat radiating member. By having the burner orifice at about the highest point in the curved portion 20 9 instead of at the closed end, there is less tendency of clogging at the orifice as the particles of foreign matter in the fuel will tend to gravitate into the pipe upon either side of the orifice rather than through said 25 orifice. Preferably the chamber 7 is located close to the base so as to provide for compactness and take advantage of the heat radiations from said base.

I claim:—

An oil burner of the character described 30 embodying in its construction a large flat base adapted to rest upon the grating in the fire box of a cook stove and having an opening therein provided for connection thereof with a fuel feed supply pipe, said plate having air intake openings on the opposite sides of the first-named openings, tubular air intake members carried by the plate and extending upwardly from said air intake opening, a generating chamber supported by the 40 plate and in communication with the first-named opening therein and a burner pipe extending upwardly from the top and near one side of said chamber and being curved outwardly and downwardly and terminating 45 in a closed end spaced well above and over said generating chamber, said pipe being closed at its upper end and provided with an outlet orifice located immediately above and over said chamber, at a point spaced from 50 said closed end, said orifice being located at the highest point in the curved portion of the pipe to prevent particles of foreign matter from clogging the orifice.

LEONARD CONOW.
